UNITED STATES PATENT OFFICE.

JOHN DAY AND ALFRED TIMEWELL, OF BLACKPOOL, AND CHARLES EDWIN TIMEWELL, OF HALIFAX, ENGLAND, ASSIGNORS TO STEPHEN SCOTT WHITAKER, OF HALIFAX, ENGLAND.

AXLE-CAP FOR WHEELS OF VEHICLES.

SPECIFICATION forming part of Letters Patent No. 626,677, dated June 13, 1899.

Application filed February 2, 1899. Serial No. 704,333. (No model.)

To all whom it may concern:

Be it known that we, JOHN DAY and ALFRED TIMEWELL, residing at Blackpool, in the county of Lancaster, and CHARLES EDWIN TIMEWELL, residing at Halifax, in the county of York, England, subjects of the Queen of Great Britain, have invented an Improved Axle-Cap for the Wheels of Vehicles, of which the following is a specification.

Hitherto considerable difficulty and trouble have been experienced in lubricating the axles of the wheels of carriages, wagons, landaus, and other vehicles, inasmuch as the caps have to be screwed off and the lubricant applied in the best manner possible. Frequently and especially with heavy vehicles a considerable portion of the lubricant is lost or wasted. By our improvements we do not remove the cap, but employ the same as a reservoir, the lubricant being admitted through an aperture formed in the same. This aperture is closed as the cap is adjusted to its proper position, and as the said cap or reservoir communicates with the axle-bearings an efficient lubrication of the parts is obtained. By these means the whole of the lubricant is utilized, and the time occupied in renewing such lubricant is reduced to a minimum.

Figure 1 is a sectional elevation of our improved axle-cap in position for receiving a supply of lubricant. Fig. 2 is a sectional end view of Fig. 1 through the line 1 2 and showing the keys and keyways for releasing and securing the loose cap. Fig. 3 is a sectional elevation showing our improved axle-cap after being supplied with lubricant and the loose cap secured and closed. Fig. 4 is a plan of our improved axle-cap opened for a fresh supply of lubricant. Fig. 5 is a view of loose cap detached.

A is an axle-cap provided with an abutment K on the inside of its outer part M and a flange H at its front end. For convenience in putting the device together the flange H can be formed in two sections, which are soldered to the part M after the device has been put together; but the device may be constructed in any approved manner which will permit its parts being placed in operative connection with each other. The flange H is provided with notches J.

B is a cap which is slidable and revoluble

in the front part M of the cap A. The cap B has a flange C at its outer end.

F is a lateral opening in the cap B, and G 55 are projections on the said cap which are free to pass through the notches J. When the cap B is moved out, as shown in Fig. 1, lubricant may be poured through the opening F. The cap is then pushed in, as shown in Fig. 3, and is secured by partially revolving it, so that the projections G pass out of line with the notches. When moved out, the cap can be held out also by partially revolving it, so that the projections are placed out of line 65 with the notches.

E is a packing-washer between the flanges D and H, which prevents the lubricant from leaking out when the cap B is pushed in.

I is a spring interposed between the abutment K and the cap B for pressing the cap B outward and sliding it when the projections are in line with the notches. 70

What we claim is—

1. The combination, with an axle-cap having a flange H at its front end provided with notches J, of a cap B the rear end of which is slidable and revoluble in the front part of the axle-cap and which is provided with a lateral opening and projections G which slide through the said notches J and engage with the flange H when the cap B is pushed in and partially revolved, substantially as set forth. 75

2. The combination, with an axle-cap having an abutment K and provided at its front end with a flange H having notches J, of a cap B the rear end of which is slidable and revoluble in the front part of the axle-cap and which is provided with a lateral opening and projections which slide through the notches J and engage with the flange H when the cap B is pushed in and partially revolved, and a spring interposed between the said abutment and the cap B, substantially as set forth. 85

In testimony whereof we, the aforesaid parties, affix our signatures in the presence of two witnesses.

JOHN DAY.

ALFRED TIMEWELL.

CHARLES EDWIN TIMEWELL.
